UNITED STATES PATENT OFFICE.

ARCH KYLE, OF KNOXVILLE, TENNESSEE, ASSIGNOR TO KNOXVILLE GLOVE COMPANY,
OF KNOXVILLE, TENNESSEE, A CORPORATION.

GLOVE.

Application filed March 12, 1927. Serial No. 174,828.

My invention relates to an improvement in gloves, particularly gloves commonly termed "workingmen's gloves," and more especially of that type shown in my Patent No. 1,437,318 of November 28, 1922, my present invention consisting in certain improvements in details whereby a glove of the type is produced of great comparative flexibility, the construction somewhat simplified and the 10 cost of production is reduced, all as will be hereinafter more fully described and claimed.

Referring to the accompanying drawing, which is made a part hereof and on which similar reference characters indicate similar 15 parts,

Figure 1 is a view of the inside of the glove before it is finished, showing the parts composing the glove after they are secured together but before the glove and fingers are 20 closed,

Figure 2, a similar view showing the outside of the glove,

Figure 3, a view showing the three finger parts at the right hand in Fig. 1, but with the 25 parts composing the fingers separated so as to illustrate the construction more clearly, and

Figure 4, a perspective view of the glove as it appears when finished, showing more 30 particularly the back of the glove.

In said drawing, the portions marked 10 represent the wrist member which may be in the form of a gauntlet or any other form desired; 11 the fabric or flannel of which the 35 main part of the glove is composed; 12 the facing for the palm of the glove, composed preferably of leather; and 13, 14, 15 and 16 the reinforcing members for the finger tips and the backs of the fingers near the tips.

The fabric 11 is preferably flannel such as 40 is commonly used in this type of glove, providing a warm, soft interior surface for contact with the hand. It is cut in one piece by a single die, as best indicated in Figs. 1 and 45 2, and is stitched at 14 to the wrist or gauntlet of the glove. The leather member 12 which forms the facing for the palm of the glove and the inside of the fingers is likewise 50 cut from a single piece of leather by a single die, and this likewise includes the facing for the inside surface of the thumb. The tips of the fingers are reinforced by the leather members 13, 14, 15 and 16 which are cut, as shown 55 in the drawing, with V-shaped cut-out portions extending from the base to a point that

will be above the knuckles of the fingers. Their meeting extremities at the crotches between the fingers are stitched together as shown. Member 16 is likewise stitched to the adjacent edge of the member 12 as is the tip 60 of member 13.

These tip members are stitched together and then also stitched to the flannel composing the backs of the fingers, the line of stitches running along the edges of the V-shaped cut in the leather. Said stitches secure said leather tips to the flannel parts forming the backs of the fingers. The leather of these parts is of a width greater than the width of the flannel finger linings and extends for a 65 considerable margin beyond the edges of the flannel so that the seams required for closing the fingers are formed in the leather only, the flannel being secured to the leather by the stitching along the edges of the V-shaped 70 openings in said leather parts. By this means a roomy flexible finger is secured, with the seams less bulky and consequently more flexible than where the fabric and leather are both confined in the seam. Moreover, a 75 considerable saving in the quantity of flannel required results, actual tests demonstrating that approximately one yard of flannel is saved in the manufacture of each dozen pairs of gloves as compared with the old method 80 employed in making this type of glove. The 85 V-shaped cut-out portion in the leather tips for the backs of the fingers permits a free movement of the fingers, and the method above described of uniting several parts insures a flexibility and free movement not obtained in gloves made by methods heretofore employed. Not only is a free movement 90 of the fingers provided for, but full protection and wearing resistance are afforded to all 95 the wearing and vulnerable parts about the fingers. In forming the leather re-enforcing parts for the fingers the dies used are designed on an interlocking arrangement, whereby the small leather re-enforcing parts 100 can be cut from scrap leather at great saving in cost.

It will be obvious to those skilled in the art that various changes may be made in my device without departing from the spirit of 105 my invention, and I therefore do not limit myself to what is shown in the drawing and described in the specification, but only as set forth in the appended claim.

Having thus fully described my said in- 110

vention, what I claim as new and desire to secure by Letters Patent, is:

A glove comprising a piece of fabric of a size sufficient to form the front and back 5 of the glove and slit along its outer edge adjacent the palm portion to form individual linings for the fronts of the fingers and slit on the same edge at the back to form individual linings for the backs of the fingers, a 10 leather reinforcing member formed to cover the palm of the glove and slit at its outer edge to form an individual covering for the front of each finger, leather reinforcing members for the backs of the fingers each 15 formed with a cut-out portion to leave the fabric covering the knuckle-joints uncovered on the backs of the fingers but covering the tips and sides of the fingers and extending to the crotch between the adjacent fingers,

said back members being stitched to each 20 other at the crotch-forming points and to the fabric forming the backs of the fingers adjacent the edges of the cut-out portions, the leather tips for protecting the backs and sides 25 of the fingers being stitched to the leather members protecting the fronts of the fingers along the meeting edges and outside the edges of the finger back linings which are joined in the seam at the finger tips only, whereby the 30 seams along the sides of the fingers are thus made of a comparatively flexible and pliable character, substantially as set forth.

In witness whereof, I have hereunto set my hand at Knoxville, Tennessee this 11th day of March, A. D. nineteen hundred and twenty. 35

ARCH KYLE,
